UNITED STATES PATENT OFFICE.

DAVID J. MONAGHAN, OF ROCHESTER, NEW YORK.

GARMENT-PATTERN.

1,171,623.

Specification of Letters Patent. Patented Feb. 15, 1916.

Application filed June 2, 1915. Serial No. 31,760.

To all whom it may concern:

Be it known that I, DAVID J. MONAGHAN, of Rochester, in the county of Monroe and State of New York, have invented a new and useful Garment-Pattern, fully set forth in the following specification and shown in the accompanying drawings.

The present invention relates to garment patterns and an object of the same is to provide a simple and inexpensive construction which will permit tailors and others who are not familiar with garment cutting to lay out a garment of any size with all the points thereon accurately positioned.

To this and other ends, the invention consists in certain parts and combinations of parts all of which will be hereinafter described, the novel features being pointed out in the appended claims.

In the drawings, there has been illustrated a number of patterns designed for making a coat for a man, Figure 1 being a plan of the front pattern; Fig. 2 being a plan of the back pattern; Fig. 3 being a plan of the undersleeve; Fig. 4 being a plan of the oversleeve; Fig. 5 being a plan of the collar; Fig. 6 being a section on the line *a—a*, Fig. 5; and Fig. 7 being a section on the line *b—b*, Fig. 5.

Each of the patterns is formed from a sheet of cardboard or other stiff flat material into a body portion 1 which has a surrounding guide edge for a marking tool, such edge including the main points for laying out a garment. This body portion is designed for laying out the smallest sized garment and, in order that the pattern may be utilized for laying out garments of other sizes, each body portion of the pattern carries adjustable members for shifting the main points to correspond with the size of the garment to be laid out. In this instance, each of these adjustable members is in the form of a slide 2 secured to the bottom portion 1 by two or more rivets 3 which are anchored in the body portion and extend through slots or guides 4 in the slides, having heads which overhang the slides. Washers 5 may, if desirable, be interposed

between the slides and the body portion to prevent friction between such parts. Each slide has its outer end movable and conforming to the point on the body portion which is to be shifted to obtain the different sized garments and each slide also is provided with an index line or mark 6 which

is adapted to coöperate with a number of divisions 7 formed on the body portion 1 to one side of each slide, said divisions being numbered to correspond with the different sizes of garments. With this arrangement, it is possible by shifting the slides so that the line 6 on each slide coöperates with a certain number, to adjust the main points on the pattern to correspond with a pattern of such number.

Referring first to the pattern illustrated in Fig. 1, 8 indicates the front and gore collar point, 9 the gore notch point, 10 the gore and collar break, 11 the shoulder and gore point, 12 the scye shoulder point, 13 the forepart scye and side seam, 14 the waist seam, 15 the spring side seam, 16 the bottom front edge, 17 the waist front, and 18 the breast front seam.

Referring next to Fig. 2, where the back pattern is shown, 19 indicates the bottom side seam point, 20 the waist side seam point, 21 the scye and side seam point, 22 the sleeve scye notch, 23 the back shoulder and scye point, 24 the neck shoulder point, and 25 indicates the neck and center seam.

Referring next to the undersleeve pattern shown in Fig. 3, 26 indicates the undersleeve scye point, 27 the elbow seam, and 28 and 29 the sleeve length.

Referring next to Fig. 4 where the pattern of the oversleeve is indicated, 30 and 31 indicate the sleeve head, 32 the oversleeve scye point, 33 the elbow seam, and 34 and 35 the sleeve length.

Referring next to the collar pattern shown in Fig. 5, 36 and 37 indicate the back points, and 38 and 39 the front points.

It will be noted that each of the slides 2 on all of the garments moves so that the point which is carried by said slide can be made to register with the adjacent edge of the body 1 and is adjustable from such point outwardly in the direction in which such point is shifted for garments of larger sizes, the end of the slide conforming to the body of the pattern at the point which is to be shifted. The use will be clearly seen from Fig. 2 where the slides are shown shifted in dotted lines and the shape of the larger sized garment is also illustrated in dotted lines at 40. This dotted line 40 is not sketched in by hand but is effected by bringing the edge of the pattern body 1 to the points which have been laid out by shifting the slides on the body portion so that the

body portion not only serves as a guide for a small sized garment but also serves as a guide for any sized garment provided for by the pattern.

5. A pattern constructed in accordance with this invention is simple in its operation and may therefore be used by tailors and others who are not familiar with the ordinary processes of laying out and grading garments. It is only necessary to know the size of the garment to be laid out, the slides being adjusted to such size and the points then marked off. The shape of the garment between such points can then be readily obtained by the guiding edge on the body portion 1.

What I claim as my invention and desire to secure by Letters Patent, is—

1. A pattern comprising a stiff flat body portion having a guide edge for a marking tool, said edge having the main layout points of a small sized garment included therein, relatively adjustable members on said body portion at the main points and each carrying a single main point for shifting the main points beyond the marking edge to lay out larger garments, and separate indicating means for each of said members for determining the adjustment.
- 20 2. A pattern comprising a stiff flat body portion having an edge for a marking tool,

the edge having the main layout points of a small sized garment included therein, relatively adjustable slides on said body portion and each having a single main point thereon 35 adapted to be brought into register with a main point on the marking edge when the slide is in its innermost position, said slides being movable to carry their points beyond the marking edge in directions which said 40 points would shift in garments of progressively increasing sizes, and indicating means for each slide for determining such shifted positions.

3. A pattern comprising a stiff flat body 45 portion having an edge for a marking tool, said edge including therein the main layout points of a small sized garment, headed rivets on said body portion, slotted slides guided by said rivets and each having a single main 50 layout point at its outer end which is adapted to register with a main layout point on the body portion when the slide is in its innermost position and is shifted by the slide 55 in the direction which said point would shift in garments of progressively increasing sizes, washers surrounding the rivets between the slides and the body portion, and indicating means for each slide for determining the adjustment of the slide.

DAVID J. MONAGHAN.

Copies of this patent may be obtained for five cents each, by addressing the "Commissioner of Patents, Washington, D. C."

It is hereby certified that in Letters Patent No. 1,171,623, granted February 15, 1916, upon the application of David J. Monaghan, of Rochester, New York, for an improvement in "Garment-Patterns," an error appears in the printed specification requiring correction as follows: Page 1, lines 68, 69, 70, and 71, the word "gore" should read *gorge*; and that the said Letters Patent should be read with this correction therein that the same may conform to the record of the case in the Patent Office.

Signed and sealed this 28th day of March, A. D., 1916.

[SEAL.]

J. T. NEWTON,

Acting Commissioner of Patents.

Cl. 33-14.
